UNITED STATES PATENT OFFICE.

ROBERT M. FRYER, OF NEW YORK, N. Y., ASSIGNOR TO GEORGE D. LEONARD AND IDA J. FRYER, OF SAME PLACE.

SCREW-PROPELLER.

SPECIFICATION forming part of Letters Patent No. 283,336, dated August 14, 1883.

Application filed November 15, 1882. (No model.)

To all whom it may concern:

Be it known that I, ROBERT M. FRYER, of the city, county, and State of New York, have invented certain new and useful Improvements 5 in Screw-Propellers, as fully described hereinafter.

The object of my invention is to increase the efficiency of the screw-propeller by preventing as far as possible the slips due to the 10 breaking up of the water, and to enable the different blades to act successively upon the same water with propulsive effect; and this I accomplish by arranging the blades spirally around a shaft or hub, giving to each succeeding 15 blade in the series an increased pitch. The spiral arrangement of the blades upon the shaft affords a space between each two blades for the passage of water, which permits the screw more readily to clear itself of broken 20 water, while the increasing pitch enables each blade to take a fresh hold upon the water which was acted upon by the preceding blade. The action of the screw-propeller tends to throw the water backward and outward, the direction 25 depending upon the pitch of the blades. It therefore follows that when the blades are arranged spirally upon the shaft as I propose to arrange them, unless the pitch be increased, each succeeding blade in the series will have 30 a less hold upon the water than the preceding one by reason of the movement of the water. In order, therefore, to equalize the action of the blades, it becomes necessary to increase the pitch so as to preserve the same relative angle 35 between the water and the working-surface of the succeeding blades.

Referring to the accompanying drawings, Figure 1 is a side elevation of a screw constructed according to my plan, and showing

the manner of applying it to a vessel. Fig. 2 40 is a rear elevation.

G is the shaft or hub upon which the blades are secured.

A, B, C, D, E, and F represent the blades, the first one, A, being arranged at any desired 45 angle or pitch. The blade B has a greater pitch than A, and C has a greater pitch than B, and so on to the end of the series. Any number of blades may be used, although four or six will probably be found in practice to be 50 the most advantageous number.

I am aware that a spiral arrangement of the blades of a propeller upon their shaft is not new, and I am also aware that continuous screws with increasing pitch have before been made; 55 but I am not aware that separate blades have ever been arranged spirally and with increasing pitch.

I am also aware that a plurality of propeller-wheels or a series of blades or floats have 60 been used, one ahead of the other, each propeller-wheel or series of blades toward the stern being provided with greater pitch than the preceding wheel or series; but

What I claim as my invention, and desire 65 to secure by Letters Patent, is—

A screw-propeller consisting of a hub provided with blades or flanges in spiral order, so as to produce for each blade or flange a separate line of rotation, each blade or flange in 70 one direction having an increased pitch as compared with the preceding blade or flange, substantially as and for the purposes set forth.

ROBT. M. FRYER.
